[**] Term: 14 Years

Primary Examiner—Susie J. Mercer
Attorney, Agent, or Firm—Howard L. Rose

[21] Appl. No.: 663,219

CLAIM

[22] Filed: Mar. 2, 1976

The ornamental design for an ionization sensor for smoke detector, substantially as shown.

[51] Int. Cl. ..... D10—05

DESCRIPTION

[52] U.S. Cl. D10/121

[58] Field of Search D10/106, 121;
340/227 R, 227.1, 228 R, 228.1, 237 R, 237 S,
258, 276
